UNITED STATES PATENT OFFICE.

JOSEPH T. RICHEY, OF PORT CLINTON, OHIO.

WRENCH.

1,281,209.

Specification of Letters Patent.

Patented Oct. 8, 1918.

Application filed April 15, 1918. Serial No. 228,728.

To all whom it may concern:

Be it known that I, JOSEPH T. RICHEY, a citizen of the United States, residing at Port Clinton, in the county of Ottawa and State of Ohio, have invented new and useful Improvements in Wrenches, of which the following is a specification.

This invention relates to wrenches, particularly to wrenches adapted for use upon nuts, bolts, and similar angular surfaces, and is furthermore adapted for use upon cylindrical objects, such as pipes and the like.

A very important object is the provision of a wrench of this character which has its pivoted jaw adjustable in respect to its fixed jaw, whereby pipes or cylindrical objects of different diameters may be operated upon, the adjustment being effected by shifting the fulcrum point of the pivoted jaw.

Another object is the provision of a wrench of this character in which the fixed jaw member and handle associated therewith is so formed as to receive and house the major portion of the pivoted jaw.

A further object is the provision of a wrench of this character which will be very simple and inexpensive in manufacture, highly efficient and durable in use, and a general improvement of the art.

With the above and other objects and advantages in view, the invention consists in the novel construction and arrangement of parts to be hereinafter more fully described and claimed, and illustrated in the accompanying drawing, in which:—

Figure 1, is a perspective view of my wrench, the parts being separated, and

Fig. 2 is a cross sectional view therethrough on the line 2—2 of Fig. 1.

Referring more particularly to the drawing, the numeral 5 designates the fixed jaw member as a whole, which comprises the handle portion 6 and the work engaging portion 7. The portion 7 is curved on its inner and outer edges, as shown, the curvature of the inner edge permitting application of the wrench to articles or work without the edge interfering therewith. The end portion 7 is formed as a hook which has its bill directed

somewhat toward the other end 6, as shown at 9. The handle portion 6 of this fixed jaw member is slotted throughout the greater portion of its length, as shown at 10. Disposed within the slot 10 in the handle portion 6 is the movable jaw member 12 which is formed as a straight bar having its free end

curved and provided with teeth, as shown at 13.

It will be seen that I have provided means whereby the movable jaw 12 may be adjusted in relation to the fixed jaw member 5. In carrying out this feature of the invention, I provide the handle portion 6 with a plurality of circular openings which communicate with transverse slots 15 extending to the inner edge of the fixed jaw member 5. These holes and slots are in the nature of key-hole slots and it will be observed that the length of the slots 15 increase progressively toward the end of the handle portion 6. Extending from opposite sides of the jaw member 12 are trunnions 16 which are substantially cylindrical and of the same diameter as the holes 14 but which have flattened sides 17. The thickness of the trunnions 16 between the flat sides 17 is the same as the width of the slots 15 so that the trunnions 17 may be passed through the slots 15 and into the holes 14. It is understood of course, that the jaw member 12 must be disposed at right angles to the inner edge of the jaw member 5 in order that the trunnions may be inserted within the slots. After the trunnions have been inserted within the selected holes, the jaw member 12 is swung toward the end 7 of the fixed jaw member, whereby dislocation of the trunnions will be prevented. The wrench may then be used in an obvious manner by engaging the hooked end 9 of the fixed jaw member at one side of the object to be turned and the toothed end 13 of the movable jaw member at the other side. In case cylindrical objects of relatively great diameter are to be engaged by the wrench, the trunnions 16 are engaged within the holes 14 nearest to the end of the handle member 6.

When the wrench is not in use and the trunnions 16 are inserted in the holes 14 nearest the end of the handle member 6, the jaw 12 will be disposed entirely within the slot 10 with the exception of its curved end 13 and the outer edge of the jaw member 12 will be flush with the open edge of the jaw member 5.

From the foregoing description and a study of the drawing, it will be apparent that I have thus provided a very simple and efficient wrench whereby angular or cylindrical objects may be gripped and turned and which is adjustable for satisfactory use upon objects having widely different dimensions.

Having thus described my invention, what I claim is:—

1. A wrench comprising a fixed jaw member terminating at one end in a hook and having at its other end a handle portion longitudinally slotted throughout its length at its inner edge, said handle portion being provided with a plurality of transversely extending circular openings and further provided with a plurality of slots communicating with the circular openings and extending to the inner edge of the handle portion and inclined toward said hook, a movable jaw member disposed within said longitudinal slot and trunnions extending laterally from said movable jaw member and disposable within said circular openings, said movable jaw member lying entirely within the confines of said fixed jaw member when the wrench is in its closed position.

2. A wrench comprising a fixed jaw member terminating at one end in a hook and having at its other end a handle portion longitudinally slotted throughout its length at its inner edge, said handle portion being provided with a plurality of transversely extending circular openings spaced progressively increasing distances from the inner edge of the handle portion, said handle portion being further provided with a plurality of slots communicating with the circular openings and extending to the inner edge of the handle portion, a movable jaw member disposed within said longitudinal slot, and trunnions extending laterally from said movable jaw member and disposed within said circular openings.

In testimony whereof I affix my signature

JOSEPH T. RICHEY.
